UNITED STATES PATENT OFFICE

HARRY C. VANTASSEL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

APPARATUS FOR THE CONTROL OF HIGHWAY-CROSSING SIGNALS

Application filed March 24, 1930. Serial No. 438,814.

My invention relates to apparatus for the control of highway crossing signals, and has for an object the provision of novel and improved controlling apparatus eliminating the necessity for insulated joints in the track rails.

I will describe one form of apparatus embodying my invention, and will then point out the novel features thereof in claims.

10 The accompanying drawing is a diagrammatic view showing one form of apparatus embodying my invention.

Referring to the drawing, the reference characters 1 and 1^a designate the track rails 15 of a railway track which is intersected by a highway H. Located at this intersection is a highway crossing signal S, which, as here shown, is an electric bell.

Located between the track rails 1 and 1^a 20 to the left of the highway H, are two transformers G^c and G^p, and located between the rails at the highway H is a third transformer G^e. Each of these transformers comprises a magnetizable core made up of two U-shaped 25 members 2 and 3; which members carry a primary winding 4, and a secondary winding 5, respectively. Each primary winding 4 is constantly supplied with alternating current from a suitable source, the terminals of which are 30 designated B and O. The parts of each transformer are so proportioned that in the absence of a car or train a given voltage is induced in the secondary 5, but that when the track immediately adjacent the transformer is occupied 35 by a car or train, the wheels and axles and the trucks shunt some of the primary flux from the secondary, so that the voltage induced in the secondary is materially reduced. One form of transformer which may be used in 40 systems embodying my invention, is disclosed and claimed in application for Letters Patent of the United States, filed by P. N. Bossart on April 9, 1930, Serial No. 442,991.

The secondary 5 of transformer G^c is directly connected with the winding of a relay C, and the secondary of transformer G^e is directly connected with the winding of a relay E. The secondary of transformer G^p is connected with the winding of a relay D 50 through a front contact 8 of this relay, so

that this circuit constitutes a stick circuit. This circuit is from the upper terminal of the secondary of G^p, through contact 8, and the winding of relay D to the lower terminal of the secondary of G^p. Associated with the relay D is a thermostat F comprising a heating winding 15 and a normally open contact 16. Winding 15 of this thermostat is provided with a circuit which passes from the upper terminal of the secondary of transformer G^p through winding 15, back contact 55 9 of relay D, and front contact 6 of relay C to the lower terminal of the secondary. Relay D is provided with a pick-up circuit which passes from the upper terminal of the secondary of G^p, through contact 16, and the winding of relay D to the lower terminal of the secondary of G^p. Thermostat F is so proportioned that the time required for its contact 16 to close after winding 15 becomes energized, is greater than the minimum time consumed by a train passing from transformer G^p to transformer G^c.

The signal S is controlled by a relay K. This relay is provided with a stick circuit 75 which passes from terminal B, through contact 7 of relay C, contact 11 of relay K and the winding of this relay to terminal O. This stick circuit is provided with a shunt around contact 7 of relay C, which shunt includes a back contact 10 of relay D. Relay K is provided with a pick-up circuit which includes a back contact 13 of relay E. The signal S is provided with an operating circuit 80 which includes back contact 12 of relay K. 85

The operation of the apparatus is as follows: When a train moving toward the right passes over transformer G^c, it will momentarily reduce the voltage applied to relay C to a sufficient amount to cause this relay to 90 momentarily open. The opening of front contact 7 will open the stick circuit for relay K, so that the latter relay will open and will remain open. The closing of back contact 12 of relay K will set the signal S into operation. When the train passes over transformer G^p, it will open relay D, but the closing of back contact 10 of this relay will have 95 no effect on the signal, because this contact is included in the stick circuit for relay K and 100

the stick circuit is already open at contact 11. The opening of relay D will close the circuit for thermostat winding 15 at back contact 9, so that after a given interval of time the pick-up circuit for relay D will become closed at thermostat contact 16, whereupon the circuit for the thermostat winding will become opened at back contact 9 of relay D. When the train passes transformer G^E , it will momentarily open relay E, and the back contact 13 of this relay will close the pick-up circuit for relay K, whereupon the stick circuit for this relay will become closed and the operation of the signal S will stop.

15 When a train moving toward the left passes over transformer G^E , it will, of course, have no effect on relay K. When this train passes over transformer G^P , it will open relay D, thereby closing back contact 10. The train 20 will pass over transformer G^C before relay D again closes, and since back contact 10 of relay D is still closed, the momentary opening of contact 7 of relay C will have no effect on relay K, and so it follows that a train 25 moving toward the left will not cause signal S to operate.

It is, of course, understood that the apparatus shown in the drawing will be duplicated to provide for the operation of signal 30 S when a train moving toward the left approaches the highway H, but the duplicate apparatus for accomplishing this result is omitted from the drawing in order to simplify the disclosure.

35 Although I have herein shown and described only one form of apparatus embodying my invention, it is understood that various changes and modifications may be made therein within the scope of the appended 40 claims without departing from the spirit and scope of my invention.

Having thus described my invention, what I claim is:

1. In combination, a railway track intersected by a highway, three normally closed 45 relays C, D and E, means controlled by a train moving along said track for successively opening relays C and D in the order named as it approaches said highway and 50 for opening relay E as it crosses the highway, means for delaying the reclosing of relay D but not of relays C and E, a signal relay K, a stick circuit for relay K including a front contact of relay C and a back contact of relay D in multiple as well as a front contact of 55 relay K, a pick-up circuit for relay K including a back contact of relay E, and a highway crossing signal controlled by relay K and set into operation when the relay is 60 open.

2. In combination, a railway track intersected by a highway, three normally closed 65 relays C, D and E, means controlled by a train moving along said track for successively opening relays C and D in the order

named as it approaches said highway and for opening relay E as it crosses the highway, means for delaying the reclosing of relay D for at least the time required for a train moving at minimum speed to traverse the distance between the points at which it influences relays D and C, a highway crossing signal, means responsive to momentary opening of relay C for setting said signal into operation, means for preventing momentary opening of relay C from setting said signal into operation if relay D is open at the time, and means responsive to momentary opening of relay E for stopping the operation of said signal.

3. In combination, a railway track intersected by a highway, two normally closed relays C and D, means for opening said relays in the order named when a train approaches said highway and in the reverse order when a train is receding from the highway, means for delaying the reclosing of relay D for at least the time required for a train moving at minimum speed to traverse the distance between the points at which it influences relays D and C, a highway crossing signal, means responsive to momentary opening of relay C for setting said signal into operation, means for preventing momentary opening of relay C from setting said signal into operation if relay D is open at the time, and means for stopping the operation of said signal when a train which has set it into operation crosses said highway.

4. In combination, a railway track intersected by a highway, three transformers G^C , G^D and G^E located in the trackway in such positions that a train moving in one direction influences transformers G^C and G^D in the order named as it approaches the highway and transformer G^E as it crosses the highway, a source of current constantly connected with the primary of each transformer and the influence of a passing train being to materially reduce the output voltage of the secondary, a relay C connected with the secondary of transformer G^C , a relay E connected with the secondary of transformer G^E , a relay D connected with the secondary of transformer G^D through a front contact of relay D, a thermostat having a winding and a normally open contact, a circuit for said thermostat winding including the secondary of transformer G^D and a back contact of relay D as well as a front contact of relay C, a pick-up circuit for relay D including the secondary of transformer G^D and the contact of said thermostat, a signal relay K, a stick circuit for relay K including a front contact of relay C and a back contact of relay D in multiple as well as a front contact of relay K, a pick-up circuit for relay K including a back contact of relay E, and a highway cross-

ing signal controlled by relay K and set into operation when the relay is open.

5. In combination, a railway track intersected by a highway, three transformers G^c , G^d and G^e located in the trackway in such positions that a train moving in one direction influences transformers G^c and G^d in the order named as it approaches the highway and transformer G^e as it crosses the highway,
- 10 a source of current constantly connected with the primary of each transformer and the influence of a passing train being to materially reduce the output voltage of the secondary, a relay C connected with the secondary of transformer G^c , a relay E connected with the secondary of transformer G^e , a relay D connected with the secondary of transformer G^d through a front contact of relay D, a thermostat having a winding and
- 15 a normally open contact, a circuit for said thermostat winding including the secondary of transformer G^d and a back contact of relay D as well as a front contact of relay C, a pick-up circuit for relay D including the secondary
- 20 of transformer G^d and the contact of said thermostat, a highway crossing signal, means responsive to momentary opening of relay C for setting said signal into operation, means for preventing momentary opening of relay
- 25 C from setting said signal into operation if relay D is open at the time, and means responsive to momentary opening of relay E for stopping the operation of said signal.

In testimony whereof I affix my signature.

35 HARRY C. VANTASSEL.
